SPLIT ACCUMULATOR MECHANISM

Eugene V. Heitlinger, Franklin Park, Ill., assignor
to Felt and Tarrant Manufacturing Company,
Chicago, Ill., a corporation of Illinois

Application January 11, 1951, Serial No. 205,445

11 Claims. (Cl. 235—144)

1

This invention relates in general to calculating machines, and more particularly to those employing an accumulator having denominational numeral wheel gears which are detained from their actuators to enable associated carrying springs to return the actuated numeral wheels to zero position.

A machine of this general character is disclosed in the co-pending application for United States Letters Patent, Serial No. 744,984, filed April 30, 1947, which comprises a key-driven "Comptometer" provided with selectively operable means for splitting the accumulator to prevent certain of its numeral wheels from being returned to zero position upon operation of the regular zeroizing handle. One portion of the machine thus may be employed for accumulating sub-totals of individual items entered while a second portion of the machine is used to accumulate a grand total by entering such sub-totals therein, and setting of this selectively operable means will enable zeroizing of the first portion of the accumulator in the usual manner while retaining the accumulated values in the second portion of the accumulator. Another feature of this prior machine is that the second portion of the accumulator subsequently may be zeroized merely by returning the selectively operable means to its normal inoperative position and without required further actuation of the zeroizing handle.

The selectively operable means referred to in this prior machine comprises a normally inoperative detent lever mounted at its lower end in each of certain denominational orders at the front of the accumulator, by means of spacer collars disposed on a transverse tie-rod, and having a rearwardly extending finger at its upper end spring-urged toward its operative position in which it will be engaged by the associated carrying spring winding gear as the latter is detained from its actuating gear during a zeroizing operation to prevent return of the associated numeral wheel to zero. This selectively operable means also includes a flattened transverse shaft engaging a central portion of such detent levers to normally retain the same in inoperative position, and a control member manually movable to operative position to rotate the shaft to permit spring movement of the detent levers to operative position and releasable for return into normal position by a spring which also rotates the shaft to return the detent levers to their normal inoperative position.

A principal object of the instant invention

2

is to simplify the construction of such split accumulator mechanism and to facilitate adding such mechanism to, or mounting the same in, an otherwise complete calculating machine of this type.

Another important object of the invention is to maintain proper horizontal alignment of the previously actuated numeral wheels of the second portion of the accumulator with their sight openings in the casing of such a machine when a zeroizing operation is effected with the split accumulator mechanism operative to prevent their return to zero position.

These objects are attained by mounting a normally inoperative detent lever assemblage in each desired denominational order of the machine on an existing transverse shaft by means of a hub portion which is secured to the detent lever and is prevented from lateral displacement in the machine by the usual intermediate skeleton frame plates. Each detent lever is formed with a spring coiled on this hub portion as a part of a unitary assemblage, with a forwardly extending curved end of the spring overlying a transverse rod regularly provided in the machine and swung forward to reset significant-digit numeral wheel indicators as an incident to any zeroizing operation. These forward ends of the detent lever springs thus are raised in response to operation of the regular zeroizing handle. Each detent lever also is provided with a rearwardly extending tail piece overlying a flattened shaft. This shaft is somewhat similar to that in the prior machine referred to, but is rotatably controlled by a manually operable control member of simplified construction requiring no additional parts to be incorporated in the regular machine of this type for mounting the same. In normal position, the main diameter of this shaft prevents lifting of the forward ends of the detent levers in response to raising of the forward ends of their springs, although the forward ends of these detent springs are always raised or compressed in response to operation of the zeroizing handle. When the flattened shaft is rotated in response to setting of the manual control member to operative position, however, such raising of the forward ends of the detent lever springs is transmitted through the springs into a lifting of the forward ends of the detent levers. These forward ends of the detent levers are so shaped and disposed relative to the denominational associated numeral wheel gears as to engage the latter to prevent return thereof to zero position when the detent levers thus are

lifted during a zeroizing operation. The forward ends of the detent levers prevent any movement of the associated previously actuated numeral wheels from their actuated and properly horizontally aligned positions by engaging the rear surfaces of the adjacent numeral wheel gear teeth with a complementally shaped cam surface formed thereon. Each carrying spring in a machine of this type tends to rotate its numeral wheel gear toward this cam surface on the forward end of the associated detent lever during zeroizing, so that return of the numeral wheel to zero position is positively prevented. Blocking of normal zeroizing action by engaging the carrying spring winding gear, as is done in the prior machine referred to, permits a certain amount of movement of the numeral wheel out of horizontal alignment with its sight opening in the machine casing because of the normal backlash in the numeral wheel gear train. The instant detent levers, however, prevent such horizontal misalignment of the numeral wheels with sight apertures, since they engage the numeral wheel gears directly to eliminate such backlash effect thereon.

Thus it will be seen that the previously recited objects of this invention are attained by means of these several structural improvements over the mechanism of the referenced prior machine. Functionally, the difference between the instant mechanism and that of the prior machine referred to is that the detent levers herein are moved to operative position by the zeroizing handle, rather than being spring-actuated to active position in response to manual setting of the control member to operative position; these instant detent levers cooperate directly with their denominationaly associated numeral wheel gears (which are rotatably mounted on a stationary shaft), rather than being engaged by their associated carrying spring winding gears as the latter are swung forwardly in zeroizing; and the detent levers thus maintain the numeral wheels in proper horizontal alignment with their sight openings in the machine casing.

Numerous other objects and advantages of the invention will be apparent as it is better understood from the following description, which, when taken in connection with the accompanying drawings, discloses a preferred embodiment thereof.

In the drawings,

Figure 1 is a side elevation of a calculating machine embodying the present invention, as seen from the right side of the machine and with parts thereof broken away to disclose the zeroizing handle and the mechanism actuated thereby and the selectively operable control member for the split accumulator mechanism;

Fig. 2 is a detail longitudinal section through the machine, as viewed from the left side thereof, showing a portion of the split accumulator mechanism, including one of the detent levers disposed in normal inoperative position and the means for moving the same to operative position in response to actuation of the zeroizing handle;

Fig. 3 is an enlarged detail section similar to Fig. 2, showing one of the detent levers restrained in inoperative position after actuation of the zeroizing handle;

Fig. 4 is a view similar to Fig. 3 illustrating the detent lever moved to operative position;

Fig. 5 is a rear elevational view of one of the detent lever assemblages;

Fig. 6 is a bottom plan view of the detent lever assemblage of Fig. 5;

Fig. 7 is a perspective view of one of the detent lever assemblages; and

Fig. 8 is a top plan view of the front portion of the machine, with the casing and most of the other mechanism omitted to facilitate illustration of the instant split accumulator mechanism, and showing the manual control member in horizontal section.

Referring more particularly to the drawings, the instant embodiment of the invention is shown for purposes of illustration as being incorporated in a calculating machine of the type commonly known as a "Comptometer" more specifically disclosed in the co-pending application for United States Letters Patent, Serial No. 744,984, filed April 30, 1947, and Patents No. 2,346,601, issued April 11, 1944, and No. 1,357,748, issued November 2, 1920. As the details of construction of this type of machine readily may be understood from these patents, a brief description of the general features thereof, and more specific explanation of such parts as are directly concerned with the operation of the present improvements, are thought to be sufficient for a complete understanding of the instant invention. The machines of the referenced patents are of the key-driven type, but it will also be appreciated that the instant invention likewise may be incorporated in similar key-responsive machines which embody the same type of zeroizing mechanism, such as that illustrated in United States Letters Patent No. 2,063,962, issued December 15, 1936.

As disclosed in these referenced patents, the various instrumentalities of the calculating machine are disposed within a suitable casing and are supported by a frame consisting essentially of side skeleton plates 22 and intermediate skeleton plates 23 (Fig. 8) disposed between the various mechanisms of the several denominational orders of the machine and secured together by suitable transverse tie-rods. For convenience, the same reference characters will be employed hereinafter as are used in the referenced prior application and Patents No. 1,357,748 and No. 2,346,601 for designating similar parts of the machine. A number of columns of nine digit keys each are provided, each key of which is indicated by reference numeral 25, and accumulator mechanism is mounted at the forward end of the machine which includes a transmitting pinion or gear 31 (Fig. 2) rotatably mounted on a transverse shaft 30, in turn journaled in the several skeleton frame plates 23, a carrying spring winding gear 32 normally in mesh with the transmitting gear 31 and rotatable on a transverse shaft 33, an intermediate gear 34 rotatable on a transverse shaft 35 and in mesh with the carrying gear 32, and a numeral wheel gear 36 in each denominational order operable in response to actuation of the digit keys 25 in the associated order through the agency of a column actuator and said train of gearing which is interposed between the latter and the numeral wheel gear. Each numeral wheel gear 36 (Figs. 2 and 8) is rotatably mounted upon a stationary transverse shaft 37 and secured to an associated numeral wheel 38. The column actuator mechanism and these numeral wheels for each denominational order are disposed in well-known manner between the several intermediate frame skeleton plates 23, and the said numeral wheel driving gear train is interposed between each

numeral wheel gear 36 and its column actuator and is adapted to be detrained from the latter to effect return of the actuated numeral wheels to zero position. Each of these numeral wheel driving gear trains includes the winding gear 32 for a carrying spring which is tensioned thereby during accumulative actuation to effect tens transferring operations, and shaft 33 for the gears 32 is supported in an auxiliary frame mechanism pivotally mounted at the front of the machine on the transverse shaft 35 for slight forward swinging movement to effect disengagement of these carrying spring winding gears 32 from their transmitting pinions 31. Such detraining movement of the swinging frame is accomplished by forward movement of a zeroizing lever or handle 71 (Fig. 1), which permits the carrying springs to return their associated numeral wheels to zero position.

This zeroizing lever or handle 71 is pivoted at its lower end on a shaft 70 journalled in the right hand side plate 22 of the machine frame. A segment 72 is fixed upon the inner end of the shaft 70 and a link 73 is pivotally connected at its rear end to the segment 72 and at its forward end to a depending lever 74 that in turn is pivoted at 75 on the fixed frame. The lower end of the lever 74 is pivotally connected by means of a short link 76 with an arm 77 rotatably mounted upon a transverse shaft 78 that is journalled in the skeleton frame members. The arm 77 is provided with a transversely extending face 79 adapted to engage a second arm 80 secured to the shaft 78. When these parts are in their normal positions of Fig. 1, a short swinging movement of the zeroizing handle 71 forwardly (to the left therein) thus will impart a rocking movement to the shaft 78 in a counterclockwise direction, as viewed in this figure. Additional rocker arms 81 (Fig. 2) are fixed in spaced relationship to each other on the transverse shaft 78 for rotation therewith. These rocker arms 81 are pivotally connected with curved links 82 having slotted shifting pivots upon a transverse shaft 83 extending through the skeleton frame members. The rocking movement imparted to the shaft 78 by the above-described forward swinging of zeroizing handle 71 will be in a clockwise direction from the normal position illustrated in Fig. 2, and the resulting forward movement of the curved links 82 (to the right in Fig. 2) effects the detraining movement of the swinging frame previously described to disengage the gears 32 from the pinions 31 to accomplish a zeroizing of the accumulator, as fully set forth in the referenced patents. It should be noted that the swinging frame carrying the carrying spring winding gears 32 remains in such forward position following release of the zeroizing handle 71 to maintain the numeral wheel driving gear trains detrained from their actuating mechanisms until a digit key 25 subsequently is actuated. All of the mechanism above referred to is old and well known in this type of calculating machine, and some further additional old mechanism will now be described which is incorporated in the machine disclosed in said Patent No. 2,346,601, the following reference numerals being the same as those employed therein for designating similar parts.

This latter patent illustrates significant-digit indicating means incorporated in such a calculating machine, a portion of which is employed herein to actuate the instant split accumulator mechanism. As also illustrated in this patent, the casing 21 of the machine is provided above, and

in transverse alignment with, each of the numeral wheels 38 with a numeral wheel sight aperture 139 (Fig. 1). As shown in Fig. 2, a link 171 and a three-armed bell crank lever 172 are operatively connected with each of the rocker arms 81 and curved links 82. Each link 171 is pivotally connected at its rear end at 173 to a rearward extension of one of the links 82, and is pivotally connected at its forward end at 174 to the lower arm of one of the levers 172. Each lever 172 is so shaped and arranged as to straddle one of the links 82 and one of the links 171, and is pivotally secured at opposite sides thereof on the transverse shaft 83. The rearwardly extending arm 15 of each lever 172 is pivotally connected at 175 to an upwardly extending link 176. The upper end of each of the links 176 is pivotally mounted on a transverse rod 177 which extends across the machine through suitable enlarged apertures in the skeleton frame plates 23 adjacent and behind the numeral wheels 38. The rod 177 is swingably suspended from the numeral wheel shaft 37 by curved levers 178 which are pivotally connected at their lower ends to the rod 177 and rotatably mounted at their upper ends on the shaft 37. Clockwise rotation of the rocker arms 81 from their normal position of Fig. 2 in response to forward swinging of the zeroizing handle 71, as previously described, will result in counterclockwise rotation of the bell crank levers 172 about the shaft 83 to lower the links 176 from their normal position of Fig. 2 which, in turn, will swing the rod 177 to the full line position of Figs. 3 and 4, since this rod is supported for arcuate movement by the levers 178 suspended from the numeral wheel shaft 37. In Patent No. 2,346,601 this forward swinging movement of rod 177 is employed to reset the significant-digit indicating members therein illustrated, but the latter are not shown herein since they form no part of the instant invention. However, this forward swinging of rod 177 in response to actuation of the zeroizing handle 71 is employed to actuate the split accumulator mechanism presently to be described.

The instant invention comprises the addition to the calculating machine, such as that above-described, of means selectively operable to prevent clearing of some of the numeral wheels 38 upon subsequent operation of the zeroizing handle 71, so that any values contained in such numeral wheels will be retained therein while the other numeral wheels in the accumulator will be returned to zero position. This means includes a zeroizing control number or key 301 (Figs. 1 and 8) located in the lower right-hand portion of the machine, extending downwardly through a suitable slot in the casing 21, and pivotally connected at its lower end to the rear end of a forwardly extending lever 302. A spring 303 is connected at its lower end to the rearward portion of this lever 302 and at its upper end to an auxiliary side plate 304 which is old in the machine, and the rear end of the lever 302 is pivotally mounted upon the transverse shaft 83, so that the spring 303 normally maintains the control member 301 in its upper, full line position of Fig. 1. The forward end of lever 302 is maintained on the shaft 83 by means of a suitable U-shaped retaining clip 305, the outer leg of which engages the lever 302, while its inner leg engages the inner surface of an adjacent portion of the right-hand main side frame 22 (Fig. 8), the transverse portion of this clip extending through a suitable cutout portion of the frame plate. The upper end of the zeroizing control

member 301 is provided with a suitable finger button 306 which is aligned longitudinally of the machine with the similar finger button provided on the zeroizing crank 71 to facilitate serial or simultaneous operation of these two control members 301 and 71. The stem of control key 301 is provided interiorly of the casing of the machine with a forwardly extending recessed lug 307 (Fig. 1), and is cut away on its rear edge to define a rearwardly extending horizontal shoulder or shelf 308. A crank arm 309 disposed adjacent the outer surface of the control key 301 is provided with an inwardly extending finger on its rear end which rests upon, and is supported by, the shoulder or shelf 308. The forward end of this crank arm 309 is rigidly secured in any suitable manner to the right-hand outer end of a flattened transverse control shaft 311 journalled in suitable apertures provided in the several skeleton frame plates 22 and 23. The left end of this transverse shaft 311 (Fig. 8) is provided with a suitable slot for engagement by a spring washer or clip 312 which also engages the outer face of the left-hand side frame 22 to retain the shaft 311, together with the crank arm 309, in assembled position. The right hand end portion of this shaft 311 extends through the apertured lug 307 of the control member 301, normally engaging a lower, rearward portion 313 of the aperture or movement-limiting recess in this lug (Fig. 1) which comprises a vertical slot for limiting upward movement of the control member 301 by its spring 303. The forward portion of the aperture in the lug 307 comprises a recess 314 communicating with the vertical slot portion 313 and shaped at its lower edge to engage the shaft 311 to retain the control member in its operative, broken line position of Fig. 1, when the control member is depressed manually against the action of spring 303 and urged rearwardly to such operative position.

The instant split accumulator mechanism also comprises a plurality of detent lever assemblies, each indicated generally by reference numeral 315, mounted respectively in selected denominational orders of the machine (herein illustrated as those at the left side thereof) on a transverse shaft 316 which extends through, and is journalled in, suitable apertures provided in the skeleton frame plates 22-23 (Fig. 8). Referring more particularly to Figs. 5, 6 and 7, each detent lever assembly 315 comprises a main body portion 317 terminating at its lateral ends in a pair of downwardly bent ears 318 which are spaced in parallel relationship from each other a distance equal to that obtaining between the adjacent auxiliary frame plates 23 so as to be slidable between the latter and prevented thereby from shifting movement transversely of the machine. Extending between, and supported at its opposite ends by, these ears 318 is a tubular hub portion 319 which extends through suitable apertures provided in the ears 318 and is secured thereto in any suitable manner. The main portion of a coiled spring 321 is wound upon this tubular hub portion 319, with the right-hand end 322 of the spring engaging against the under surface of the transverse part of the main body portion 317. The left-hand end 323 of the spring 321 extends forwardly from the hub 319 and is maintained longitudinally spaced from the left-hand ear 318 by a suitable ring or spacer washer 324 mounted on the tubular hub 319. It will be understood that the spring 321 and the ring

324 are slidably mounted upon the hub 319, and it is preferred that the hub 319 have a relatively tight sliding fit in the apertures in the ears 318 to provide a unitary assemblage that still may be disassembled, if necessary, without requiring any special equipment. The main body portion 317 is provided with a rearwardly and slightly downwardly extending finger 325 and a forward extension 326 formed integrally therewith in alignment with each other. The under surface of this forward extension 326 is provided with a slot 327 milled, stamped or otherwise suitably formed therein and of sufficient width to accommodate a central portion of the left-hand end extension 323 of the spring 321 to maintain this part of the spring in longitudinal alignment and engagement with the forward extension 326 of the detent lever assemblage. The extension 326 of the detent lever terminates at its forward end in an upturned nose 328 having an angularly disposed cam surface 329 (Fig. 3) at its forward outer edge. The left-hand end portion 323 of the coiled spring 321 is reversely bent forwardly and downwardly from its point of engagement in the aligning slot 327 and terminates at a point spaced forwardly from the forward end or nose 328 of the detent lever.

As best seen in Figs. 2, 4 and 8, the tubular hub portion 319 of each of these detent lever assemblies 315 is pivotally mounted upon the transverse shaft 316 and the forwardly extending end 323 of the coiled spring 321 rests upon the transverse rod 177, the rod normally engaging that portion of this forward extension of the spring which is disposed in the slot 327 just rearwardly of its reversely bent terminal portion (Fig. 2). In such normal or inoperative position, the rearward extension or finger 325 of each detent lever overlies, and is slightly spaced upwardly from, the transverse control shaft 311. This control shaft 311 is provided with a flattened portion 331 extending throughout its length which is normally disposed in the position shown in Figs. 2 and 3 when the selectively operable control member 301 is in its normal, full line position of Fig. 1. The shaft 311 also is provided adjacent the right-hand skeleton frame plate 22 (Fig. 8) with an annular groove 332 to provide clearance for the swinging movement of the upper portion of the zeroizing lever 74.

The several parts of the instant split accumulator mechanism above described and designated by reference numerals 301, 302, 303, 309, 311 and 315 correspond generally in function to the parts identified, respectively, in application Serial No. 744,984 referred to by reference numerals 201, 202, 203, 209, 211 and 215.

The operation of the instant split accumulator mechanism is as follows. With the selectively operable manual control member 301 in its normal, full line position of Fig. 1, the crank arm 309 has its inwardly extending rearward end resting upon the shoulder 308 to maintain the transverse control shaft in its position of Figs. 2 and 3. Downward and rearward swinging movement of the upper end of this zeroizing control member 301 to its operative, broken line position of Fig. 1 against the action of spring 303 will result in the rearward end of crank arm 309 being lowered to its broken line position of Fig. 1, and such movement of crank arm 309 results in the flattened portion 331 assuming a horizontal position, as illustrated in Fig. 4. Subsequent forward swinging of the zeroizing crank or handle 71 from its normal position of Fig. 1, as

previously described, will swing the transverse rod 177 from its normal position, as shown in Fig. 2 and in broken lines in Fig. 3, to the operative position illustrated in full lines in Figs. 3 and 4. As has also previously been described, this control rod 177 remains in such forward operative position upon release of the zeroizing handle 71 and return thereof to its normal position of Fig. 1 and until any one of the digit keys 25 subsequently is depressed to effect an accumulative actuation. Movement of the transverse control rod 177 from its normal or inoperative position to its forward, operative position of Fig. 4 thus will result in lifting of the forward nose ends 328 of all of the detent levers 315 into engagement with an adjacent tooth of the associated numeral wheel gears 36 through the agency of the forwardly extending ends 323 of the coiled springs 321 of the several detent lever assemblages. However, if the transverse control shaft 311 is disposed in its normal position of Fig. 3 when such actuation of the zeroizing handle 71 is effected, the resulting forward swinging of the transverse rod 177 from its broken line to its full line position of Fig. 3 will result only in tensioning or lifting of the forwardly extending ends 323 of the several detent lever springs 321, since engagement of the detent levers with their numeral wheel gears 36 will be prevented by contact of the rearwardly extending fingers 325 of the detent levers with the outer diameter of the transverse control shaft 311, as shown in this figure. In other words, each time that the zeroizing handle 71 is actuated to effect zeroizing of the accumulator, all numeral wheels in those denominational orders having no detent lever 315 will be returned to zero position, and whether or not the numeral wheels 38 will be returned to zero in those denominational orders of the accumulator in which detent levers 315 are provided, will depend upon the position in which the zeroizing control member 301 is disposed. If this control member 301 is in its normal full line position of Fig. 1, the numeral wheels in all orders of the accumulator will be zeroized. However, if the control member 301 is in its operative, broken line position of Fig. 1, the detent levers 315 will be moved to their blocking position of Fig. 4 and retained therein to prevent return of their associated numeral wheels 38 to zero position.

Following operation of the zeroizing crank 71 with the control member 301 in its operative, broken line position of Fig. 1, depression of any one of the digit keys 25 will effect re-engagement of all of the numeral wheel gear trains with their column actuators and return of the transverse rod 177 rearwardly to its normal inoperative position of Fig. 2. This will enable the several detent levers 315 to be returned by gravity to their normal inoperative positions of Fig. 2, and subsequent actuations of zeroizing handle 71 similarly will effect, or not effect, zeroizing of the numeral wheels in those orders in which detent levers 315 are disposed, depending upon the particular setting of the zeroizing control member 301.

It may be that an operator, after having zeroized the right-hand portion of the accumulator while preventing return of the numeral wheels in the left-hand portion thereof to zero position, will desire to zeroize these latter numeral wheels, and such may be accomplished merely by manually returning the control member 301 from its broken line to its full line position of Fig. 1. This will permit the spring 303 to lift the rear

end of crank arm 309 from its position of Fig. 4 to its position of Fig. 3. The spring 303 is of sufficient strength to overcome the several springs 321, so that such lifting of the rear end of crank arm 309 will cam the tail pieces 325 of all of the detent levers 315 upwardly to move the latter to their position of Fig. 3 to disengage the detent noses 328 from their associated numeral wheel gears 36. The carrying springs in these denominational orders of the accumulator will thereby be permitted to return their respective numeral wheels to zero position.

It is thought that the functional differences and advantages of the instant mechanism over that disclosed in application Serial No. 744,984 referred to will be fully appreciated from the preceding description. The structural differences and advantages of the instant mechanism over that disclosed in said application are manifold. It is extremely desirable to be able to add the instant split accumulator mechanism to any desired denominational orders of an otherwise complete calculating machine of the present type. This is a simple matter with the present mechanism, since it is necessary only to incorporate in the regular machine suitable apertures in the frame plates 22 and 23 for receiving the transverse shaft 311. Such a machine thereafter may be converted to employ the instant split accumulator mechanism in any desired denominational orders merely by removing the casing 21, inserting the transverse control shaft 311, mounting its manually operable control members 301-303, 305-309, and partially removing the shaft 316 and slidably replacing it in the machine while serially placing detent lever assemblages 315 thereon between the auxiliary skeleton frame plates 23 confining such desired denominational orders of the accumulator. It will be understood, of course, that the simplified construction of the members for controlling the position of the shaft 311, such as key 301, not only facilitates the mounting thereof in a standard machine of this type, but also the manufacture of these parts. The latter advantage results from the design of these parts requiring only simple stamping operations for their manufacture. And the mounting of a spring 321 as part of each detent lever assemblage 315 eliminates the necessity of independently mounting such springs in the machine and insures retention of these springs in proper operative relationship at all times. Also, since the flattened portion 331 extends substantially the full length of control shaft 311, the detent lever assemblages 315 may be mounted in any desired order or orders of the machine.

The additional feature provided by the instant split accumulator mechanism of insuring proper horizontal alignment of the indicating indicia on the non-zeroized numeral wheels 38 with their sight apertures 139 in the machine casing after the remaining numeral wheels have been zeroized is extremely important. As previously mentioned, engagement of suitable members similar to the present detent levers 315 with any members of the numeral wheel gear trains such as the carrying spring winding gears 32 in the desired denominational orders, in which zeroizing of the numeral wheels is to be prevented upon actuation of the zeroizing crank 71, other than the numeral wheel gears 36, will result in the previously actuated numeral wheels becoming misaligned horizontally with their sight apertures 139 by virtue of the normal backlash in such numeral wheel gear trains permitting a

slight rotational movement of the numeral wheels by their carrying springs. While such partial rotation of the numeral wheels due to backlash in the numeral wheel gear trains is very short in angular displacement of the numeral wheel gears 36, being substantially less than the width of one of the teeth of such gears, it is amplified in effect of resulting misalignment of the indicia on the numeral wheels relative to the lower edges of the sight apertures 139 because of the difference in diameters between the numeral wheels 38 and their gears 36. Such misaligned position of a numeral wheel is illustrated in Fig. 3, wherein the numeral wheel gear 36 has been over-rotated in a clockwise direction an arcuate distance of slightly less than that subtended by one of the teeth of this gear. It is true that the numeral wheels will assume such misaligned position when zeroized, and it is the zero position of the numeral wheel which is illustrated in Fig. 3, but such is of no importance because a machine operator is not required to scan the accumulator for an answer or result when the same has been zeroized. However, the operator is required to scan the accumulator to determine the accumulated values indicated in those denominational orders in which detent levers 315 have been rendered effective following manipulation of the zeroizing crank 71. Therefore, the upper edge of the nose 328 of detent lever 315 is provided with the cam surface 329 previously described which is so disposed relative to the associated numeral wheel gear 36 that upward movement of this forward end of the detent lever from its position of Fig. 3 into engagement with the associated numeral wheel gear 36, as illustrated in Fig. 4, will impart a partial rotation to the numeral wheel gear in a counterclockwise direction sufficient to overcome the above-described partial rotation in a clockwise direction by the carrying spring due to the backlash in the associated gear train. It will be understood, of course, that the above discussion is primarily only explanatory in nature, since during normal operation of the detent levers 315 the upper edge portions of the cam surfaces 329 will become engaged with their associated numeral wheel gears 36 prior to complete disengagement of the carrying spring winding gears 32 from their pinions 31. But for this design of the nose portions of the detent levers 315 and their engagement directly with the numeral wheel gears 36, such misalignment of the indicia on the previously actuated numeral wheels would require downward lengthening of the sight openings 139 in the casing of the machine, in order to enable an operator accurately to scan those numeral wheels following a zeroizing of the other denominational orders of the accumulator not having the detent levers 315. The instant mechanism, however, assures proper horizontal alignment of the numeral wheel indicia in those orders in which the detent levers 315 have been operatively actuated, maintaining the same alignment relative to the sight apertures 139 as obtained just prior to actuation of zeroizing handle 71.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a calculating machine having a multi-denominational order accumulator with a numeral wheel, a numeral wheel driving gear train and a carrying spring in each order, an actuator for said accumulator including a transmitting gear normally in mesh with each said gear train, and zeroizing means selectively operable manually to detrain said gear trains from said transmitting gears to permit said carrying springs to return the actuated said numeral wheels to zero position to clear said accumulator; means for splitting said accumulator to prevent clearing of said numeral wheels in certain denominational orders, comprising detent means mounted in each of said certain orders, means operable by said zeroizing means to move said detent means into engagement with their associated said gear trains as the same are so detrained, and control means normally disposed in operative position to block such movement of said detent means by said last means and selectively movable manually to inoperative position to enable such gear train engaging movement of said detent means by said zeroizing means.
2. In a calculating machine having a multi-denominational order accumulator with a numeral wheel, a numeral wheel gear, a carrying spring and a carrying spring winding gear meshing with said numeral wheel gear in each order, an actuator for said accumulator including a transmitting gear normally in mesh with each said winding gear, and zeroizing means selectively operable to detrain said winding and transmitting gears to permit said carrying springs to return the actuated said numeral wheels to zero position to clear said accumulator; means for splitting said accumulator to prevent clearing of said numeral wheels in certain denominational orders, comprising a detent lever assemblage mounted in each of said certain orders, means operable in response to operation of said zeroizing means for moving said detent lever assemblages into engagement with their associated said numeral wheel gears, and control means normally disposed in operative position to block such movement of said detent lever assemblages by said last means and selectively operable manually to inoperative position to enable such movement of said detent lever assemblages into engagement with said numeral wheel gears in response to operation of said zeroizing means.
3. A calculating machine according to claim 2, wherein each said detent lever assemblage comprises a pivotally mounted detent lever having one end disposed for swinging movement into engagement with its associated said numeral wheel gear, and a coil spring secured thereto and having one end spaced therefrom for engagement by said detent lever assemblage moving means.
4. A calculating machine according to claim 3, wherein said control means comprises a shaft mounted transversely of the machine for engagement by a rear end of each of said detent levers and having a flatted portion alignable with said rear ends of said detent levers by rotation of said shaft, and a zeroizing control key manually operable to effect rotation of said shaft to selectively dispose the same in blocking or unblocking position relative to said rear ends of said detent levers.
5. In a calculating machine having a multi-denominational order accumulator with a numeral wheel, a numeral wheel driving gear train and a carrying spring in each order, laterally

spaced frame plates separating adjacent said orders and having transversely aligned apertures therein, a transverse shaft extending through certain of said apertures, an actuator for said accumulator including an actuating gear normally engaged with each said gear train, and zeroizing means selectively operable to detract said actuating gears and said gear trains to permit said carrying springs to return the actuated said numeral wheels to zero position to clear said accumulator and including a transversely extending control rod; means readily mountable in said machine to enable selective splitting of said accumulator to prevent clearing of said numeral wheels in certain denominational orders in response to operation of said zeroizing means, comprising a flattened control shaft insertable transversely of the machine through certain of said apertures in said frame plates in adjacent parallel relationship to said transverse shaft and having a crank arm mounted on one end thereof, a selectively movable control member mountable on a said frame plate for engaging said crank arm to maintain said control shaft in operative or inoperative position, and a unitary detent lever assemblage mountable on said transverse shaft in each of said certain orders, comprising a detent lever having a hub portion rotatable on said transverse shaft and engageable with adjacent said frame plates to limit movement longitudinally of the shaft, a first end portion engageable with the denominationaly associated said gear train, and a second end portion engageable with said control shaft, and a coil spring mounted on said hub portion and having one end engaging said first end portion of said detent lever and terminating in a curved portion spaced from said detent lever and engageable with said control rod.

6. A calculating machine according to claim 5, wherein said control member comprises a key stem having a movement-limiting recess surrounding said control shaft and a shoulder engaging said crank arm, and a spring for normally maintaining said key stem in a raised position to retain said control shaft in operative position and operable to retain said key stem in a depressed position by maintaining a portion of said recess engaged with said control shaft to maintain the latter in inoperative position to which it is rotated in response to depression of said control key.

7. In a calculating machine having a multi-denominational order accumulator, means for zeroizing said accumulator, and selectively operable means for preventing zeroizing of certain of said denominational orders of said accumulator; a unitary detent lever assemblage mounted in each of said certain denominational orders as part of said selectively operable means, comprising a detent lever having a substantially U-shaped main body portion terminating in laterally spaced legs, a hub comprising a tubular member spaced from said main body portion and supported at its opposite ends by said legs, said main body portion having a rearwardly extending finger and a forwardly extending arm formed integrally therewith, and a coil spring mounted on and surrounding said tubular member and having a first end engaging said main body portion and a second end engaging said forwardly extending arm and terminating in a bent portion spaced from said detent lever.

8. A detent lever assemblage according to claim 7, including a spacer member interposed be-

tween said second end of said coil spring and the adjacent said leg of said detent lever to maintain said spring on said tubular member with said second end in longitudinal alignment with said forwardly extending arm.

9. A detent lever assemblage according to claim 3, wherein said forwardly extending arm is provided with a recess in that surface thereof adjacent said hub portion for receiving that portion of said second end of said spring engaging said arm to prevent lateral shifting of said second end of said spring relative to said arm.

10. In a calculating machine having a multi-denominational order accumulator with an indicia-bearing numeral wheel, a numeral wheel gear, a carrying spring and a carrying spring winding gear meshing with said numeral wheel gear in each order, an actuator for said accumulator including a transmitting gear normally in mesh with each said winding gear, a casing having a plurality of sight apertures each associated with a said numeral wheel and so disposed as to be aligned horizontally with the indicia thereon upon actuation of said accumulator, and zeroizing means selectively operable to detract said winding and transmitting gears to permit said carrying springs to return the actuated said numeral wheels to zero position to clear said accumulator; means for splitting said accumulator to prevent clearing of said numeral wheels in certain denominational orders and for maintaining horizontal alignment between the indicia on said actuated numeral wheels in said certain orders and said sight apertures while preventing clearing of such wheels, comprising detent means mounted in each of said certain orders and including a pawl disposed adjacent the denominationaly associated said numeral wheel gear, means operable in response to operation of said zeroizing means for moving said pawls into engagement with their associated said numeral wheel gears to prevent movement of their numeral wheels relative to said sight apertures, due to such detraining of said winding and transmitting gears, and control means normally disposed in operative position to block such movement of said pawls by said last means and selectively movable to inoperative position to enable such movement of said pawls into engagement with said numeral wheel gears in response to operation of said zeroizing means.

11. A calculating machine according to claim 10, wherein the numeral wheel gear-engaging end of each of said pawls is provided with a cam surface opposing rotation of the associated said numeral wheel gears in the direction normally effected by said carrying springs in returning the same to zero position and operable to insure proper horizontal alignment of the numeral wheel indicia with said sight apertures in said certain orders following clearing of the remaining orders of said accumulator.
